UNITED STATES PATENT OFFICE

2,538,204

SHIPPING BOX FOR CLOTHING

Robert C. Lemon, Chicago, Ill., assignor to Maxwell Brothers, Inc., a corporation of Illinois

Application December 18, 1948, Serial No. 66,031

5 Claims. (Cl. 206—7)

1

This invention relates to a shipping box for clothing suspended on hangers, and has for its principal object to provide a light, strong, durable, collapsible box that will hold clothing throughout shipment, or during storage, in such manner that the clothing will require no pressing, but may be transferred from the box directly to racks for display and sale.

Fig. 1 is a perspective view of the box and contents forming a complete shipping package, a corner portion being broken away to show the interior;

Fig. 2 is a perspective view with the parts separated and displaced to show the constituents separately, but in positions indicating how they should be assembled;

Fig. 3 is a perspective view of filler pieces used between the top and sides and the adjacent garments for holding the latter in place;

Fig. 4 is a perspective view of the constituent parts assembled in a package for storage and shipment;

Fig. 5 is a diagrammatic side elevation of the box with the top and bottom closures partly assembled with the body;

Fig. 6 is a similar view with the parts completely assembled; and

Fig. 7 is an enlarged fragmentary section on the line 7—7 of Fig. 1.

The body 10 of the box has four sides 11, 12, 13, and 14, each provided with flaps or flanges 15 and 16 at the top and bottom respectively, the material being scored between the sides and the flaps to make the bends or angles straight and regular.

The bottom closure of the box is composed of two like sheets 17 and 18, each having flaps or flanges 19 and 20 formed by scoring at 21 and 22 and stiffened or strengthened along the free edge by a strip or board of wood 23, or other fibrous or molded material, made fast thereto.

In the course of assembly of the bottom with the body 10, the upper bottom sheet or piece 17 is brought into the position shown at the bottom of Fig. 5, and its flaps or flanges, with the reinforcing strips, are folded across the edges of the flaps 16 on opposite sides of the body 10, moving through the positions shown in lower right and the lower left, and finally to the position shown at the bottom of Fig. 6.

The lower bottom sheet or piece 18 is laid across the upper bottom sheet 17 and put through similar operations to assemble its flanges with the other flanges 16 of the body portion 10, after which the folded flanges or flaps

are bound by binder strip 25 to make the bottom closure secure.

In the normal course of assembly, the operations described are preceded by turning the body portion 10 upside down and assembling the bottom as though it were the top.

In order to support the clothing in the box, a hanger bar 26 for hangers 27 is provided at the top and suspended from two side walls, such as 11 and 13, by hanger bar supports consisting of wooden slats or boards 28, notched at 29 and secured to strips 30, scored and folded at 31 to provide flanges or flaps 32 adapted to fit over the upper ends of the walls 11 and 13 and lie alongside of the downturned flaps or flanges 15 (Figs. 5, 6, and 7).

The top closure is composed of two sheets or pieces 33 and 34 having flaps or flanges 35 formed by scoring at 36 and 37 and adapted to 20 be interfolded with the flaps 15 of the walls 11 and 13 and 32 of the hanger bar support.

In the course of assembly of the top closure, the inner or lower top sheet 33 is put in place, as indicated in Fig. 5, on top of the hanger bar 25 and hanger bar supports, and the flaps are progressively folded from the position shown in the upper left in Fig. 5 through that shown in the upper right to the final position shown at the top of Fig. 6, after which the parts are bound by binder strip 40 similar to that shown in 25.

In the shipping package, the suits or other clothing 41, together with the hangers 27, on which the same are supported from the bar 26, 35 are held in place by filler pieces 42 made by folding a strip or a sheet into triangular form by bending it at scored lines 43, 44, and 45, and overlapping the end portions 46 and 47, as best shown in Fig. 3.

40 All of the constituents of the box, except the stiffening or reinforcing strips or boards 23, the hanger support 26, and the hanger support slats or boards 28, are made of a suitable grade of corrugated or solid fiberboard, or the like. For 45 larger sizes, double faced corrugated boards, 200 to 275 pound tests, will make satisfactory parts. But, of course, the choice of material may be varied greatly according to the use for which the box is to be put. Likewise, the reinforcing strips, hanger bars, and hanger bar supports 50 may be made of whatever material is most readily available.

The body 10 will include one or more manufacturers' joints 50 made by tape, or by lapping and stitching.

The top and bottom closures are preferably made in two pieces, as shown and described, because that gives double thickness at the ends, but under appropriate conditions the enclosures may each be made in one piece with corner portions cut away to provide the flaps or flanges.

The constituent parts, shown in Figs. 2 and 3, make up a shipping package substantially as shown in Fig. 4. The body portion 10 is collapsed and folded to approximately the width of one side and the length of one side with the flaps 15 and 16, and forms the bottom of the package. On top of that folded body portion are placed the sheets which make up the filler pieces 42. On top of those are placed the four sheets 17, 18, 33, and 34 forming the top and bottom closures; on top of those, the hanger bar supports and the hanger bar. The assembly is bound by binder strips 51 and 52.

A shipping box suitable for 15 men's suits will make a shipping package such as shown in Fig. 4 of approximately 48" x 22" x 1 3/4".

As here shown, the sheets 17 and 18 forming the bottom are provided with strengthening strips 23, while the sheets 33 and 34 forming the top closure have no such strips. This is by way of illustration. Each may be provided with strips, or one may be provided with strips, and the other not, or both may be without strips without departing from the spirit of the invention.

As a rule, the hanger bar and hanger bar supports, which together form an I-shaped frame, interlocked with the structure of the top closure gives sufficient strength to the top of the box without the additional reinforcing strips corresponding to those shown in 23 on the bottom closure.

Suspending the hanger bar supports along the upper, inner edges of the opposed side walls 11 and 13 and binding the whole with the binder 40 gives a support that readily sustains the weight of the clothing in shipping and maintains the top structure intact.

The binder strips 25 and 40 may be varied greatly, but 3/8" x .012" flat strap has been most satisfactory.

I claim:

1. In a shipping box, a body having opposed side walls spaced apart, a hanger bar support along the inner face of each said side wall having a flap extending over the top of said side wall and downwardly against the outer face thereof, a hanger bar on said supports and extending across the space between them, and a top closure across the top of the body and having flaps extending downwardly along the outer edges of said opposed walls and holding said support flaps against said walls.

2. In a shipping box, a body having opposed side walls spaced apart, a hanger bar support along the inner face of each said side wall having a flap extending over the top of said side wall and downwardly against the outer face thereof,

a hanger bar on said supports and extending across the space between them, a top closure across the top of the body and having flaps extending downwardly along the outer edges of said opposed walls and holding said support flaps against said walls, and filler pieces of prismatic shape under the top closure between the hanger bar and the said opposed side walls.

3. In a shipping box, a body having opposed side walls spaced apart, a hanger bar support along the inner face of each said side wall including a bar extending along said face and suspended by a folded strip having a flap extended over the top of said side wall and downwardly against the outer face thereof, a hanger bar on said supports and extending across the space between them, and a top closure across the top of the body and having flaps extending downwardly along the outer faces of said opposed walls and holding said support flaps against said walls.

4. In a shipping box, a body having opposed side walls spaced apart, a combined top reinforcement and hanger support including a hanger bar support extending along the inner face of each said side wall having a flap extending over the top of said side wall and downwardly against the outer face thereof, a hanger bar extending across the body between said hanger bar supports and forming with them an I-shaped frame, and a top closure across the top of the body over the said reinforcement and hanger support and having flaps extending downwardly along the outer faces of said opposed side walls and holding said support flaps against said walls.

5. In a shipping box, a body having opposed side walls spaced apart, a hanger bar support supported by and suspended along the inner face of each said side wall by means of portions thereof hooked over the upper edge of said side walls, a hanger bar on said supports and extending across the space between them, and a top closure across the top of the body and having flaps extending downwardly along the outer faces of said opposed side walls over said hooked portions and upwardly under flaps turned down from the top of said side wall.

ROBERT C. LEMON.
